UNITED STATES PATENT OFFICE

ROBERT C. ALLEN, OF SWARTHMORE, PENNSYLVANIA, ASSIGNOR TO WESTINGHOUSE ELECTRIC & MANUFACTURING COMPANY, A CORPORATION OF PENNSYLVANIA

TURBINE BLADING

Application filed March 21, 1928, Serial No. 263,452. Renewed July 20, 1929.

My invention relates to elastic fluid turbines and more particularly to the manner of arranging the lashing with respect to the blading thereof, and it has for an object, to 5 improve the efficiency of apparatus of this character.

During the operation of an elastic fluid turbine, pulsations often occur at, or near the frequency of the blading system, and hence, 10 have a tendency to produce objectionable vibrations in the blading. It is well known that this vibration of the blading may be reduced by either increasing, or decreasing the elastic scale of the blade system so that, either 15 a higher, or a lower natural frequency of vibration will be secured. In either of the above ways, pulsations in fluid flow may be prevented from occurring in synchronism with any vibration of the blades which may 20 take place and thus, it may be assured that the frequency of the pulsations of fluid flow will be relatively far removed from the natural frequency scale of the blade system.

As a general proposition, it is generally 25 considered better to increase the elastic scale of the blade system rather than to decrease it, for in the latter case the blades would have to be made lighter and would be less able to withstand the various bending stresses. It 30 is also believed to be well established that the function of lashing wires is to increase the elastic scale of the blade system so that a higher natural frequency of vibration will be secured. This requires that a lashing wire 35 of relatively high bending resistance be used, and that the wire be fastened to the blade so that there is no relative motion or local deflection of the blade.

A more specific object of this invention, 40 therefore, is to provide for increasing the elastic scale of turbine blading by means of a lashing having a relatively high bending resistance, which may be secured to the blades so that there will be no relative motion of the lashing with respect to the blade at the point where it is fastened to the latter and no local deflection of the blade.

Another object is to so arrange the lashing 50 with respect to the blading as to utilize sub-

stantially the maximum elastic scale of the lashing.

These and other objects are effected by my invention, as will be apparent from the following description and claims taken in connection with the accompanying drawings, forming a part of this application, in which:

Figs. 1 and 2 are sectional elevations of turbine blading.

Figs. 3 and 4 are diagrammatic views illustrating the principles of my invention, and;

Fig. 5 is a sectional elevation of turbine blading having multiple lashing applied thereto.

According to my invention, a lashing wire 65 of relatively high bending resistance is fastened to the blades at the point where the tangent to the deflection curve for each blade moves through the greatest angle. Where a single lashing element is used, this method 70 of locating it brings it near to the tip of the blade, but where multiple lashings are used they are located in a similar manner, one near the tip, and the other, or others at points near the nodes, and where the tangents to the deflection curve move through the greatest angle. In this way, it is possible to obtain a 75 double bend in the lashing and thus, to utilize its maximum elastic scale.

Considering the various ways in which 80 blades can vibrate, the fundamental mode of vibration is the one in which the blades vibrate about the spindle as a node. In Figs. 1 and 2 of the drawing, I show the blades 10 mounted in the rotor 11. A lashing element 35 12, preferably a lashing wire of relatively high bending resistance, is secured to the blades.

In Fig. 2, the blades 10 are shown at one 90 extremity of their amplitude for their fundamental mode; and, in Fig. 3, the curve 13 represents the deflection curve for one of the blades shown in Fig. 2. From an inspection of the latter figure, it will be obvious that a tangent, such as the tangent line 13'; drawn 95 to the curve 13 at the end thereof, as indicated by the point 14, will move through the greatest angle as the blades vibrate, assuming that the deflection curve 13 is taken for one extreme position of the blades. The hole for 100

lashing is located on each blade at a point as near as practical to the point 14 and is, preferably, located in a relatively heavy part of the blade, and the lashing wire 12 is inserted through this hole so that the central line of the wire is at right angles to the axis of the blade at the point where the wire passes through. The wire may then be secured to the blade by means of silver solder, or in any other approved manner.

10 By fastening the wire to a relatively thick portion of the blade, it is assured that local deflection of the blade will be minimized or will not occur and furthermore, when the 15 blades attain a position during vibration such as that shown in Fig. 2, the lashing wire 12 will be forced to take a double bend, and thus, the maximum elastic scale of the wire will be effective while, at the same time, the wire 20 where it passes through the blade being normal to the axis of the blade, will have little tendency to move relative to the blades.

25 The location of the lashing as shown in Figs. 1 to 3 also provides the most effective resistance to vibration of the next higher mode above the fundamental mode in which the greatest angle of deflection is in the free 30 end portion of the blade.

35 In Fig. 4, I show the manner of locating the points for attaching the lashing where multiple lashings are used, and in Fig. 5 I show blades having lashing members 12' and 19 fixedly secured thereto. In this embodiment, the outer lashing 12' is located in the same manner as described with reference to Fig. 3 for the fundamental mode of vibration, that is, at the point 15 near the free end. However, it will be observed that the deflection curve 16 is now vibrating at the 40 second higher mode of vibration, in which case the inner lashing 19 should be located at the point 17, which is the point at which the tangent 18 to the deflection curve, drawn in the vicinity of the middle node, moves 45 through the greatest angle. In this way, it is assured that the inner lashing wire will be fully effective, which, of course, would not be the case if it were located at some other point as for example at an anti-node. Deflection 50 at the outer node 21 is sufficiently opposed by the outer lashing at 15.

55 While I have shown my invention in several forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically 60 set forth in the appended claims.

What I claim is:—

1. In a turbine, the combination of a plurality of blades, each blade having an opening formed therein at a point where the tangent to the deflection curve for a mode of

vibration defines approximately the greatest angle with respect to the normal blade radius, and a lashing member passing through the blade openings and fixedly secured to the blades so that its bending resistance opposes 70 deflection of the blades.

2. In a turbine, the combination of a row of blades, each blade having an opening formed therein at a point where the tangent to the deflection curve for a mode of vibration defines approximately the greatest angle with respect to the normal blade radius, and a lashing member having high bending resistance, passing through the blade openings, and fixedly secured to the blades so that its bending resistance opposes deflection of the blades. 75

80 3. In a turbine, the combination of a row of blades, each blade having an opening formed in the thick portion thereof and at a point where the tangent to the deflection curve for a mode of vibration defines approximately the greatest angle with respect to the normal blade radius, and a lashing member fitting closely said openings and fixedly secured to the blades so that its bending resistance opposes deflection of the blades. 85

90 4. In a turbine, the combination of a plurality of blades in a row, each blade having openings formed therein at points where the tangents to the deflection curve for a mode of vibration higher than the fundamental mode define approximately the greatest angles with respect to the normal blade radius, and lashing members passing through 100 the blade openings and fixedly secured to the blades so that their bending resistance opposes deflection of the blades.

105 5. In a turbine, the combination of a plurality of blades in a row, each blade having openings formed therein at points where the tangents to the deflection curve for a mode of vibration higher than the fundamental mode define approximately the greatest angles with respect to the normal blade radius, 110 and lashing members having high bending resistance passing through the blade openings and fixedly secured to the blades so that their bending resistance opposes deflection of the blades. 115

120 6. In a turbine, the combination of a plurality of blades in a row, each blade having an opening formed therein and a second opening formed therein approximately at the middle node of vibration at the second higher mode above the fundamental mode, and lashing members passing through the respective blade openings and fixedly secured to the blades so that their bending resistance opposes deflection of the blades. 125

In testimony whereof, I have hereunto subscribed my name this 15th day of March, 1928.

ROBERT C. ALLEN.
